RECORDING AND REPRODUCING DEVICE
AND METHOD

Alexander B. Clepton, Enid, Okla.

Application August 14, 1940, Serial No. 352,638

4 Claims. (Cl. 179—100.2)

My invention relates to improvements in apparatus and method for electro-magnetically recording and reproducing, and particularly to arrangements of this character contemplating the imposing on and reproduction from a wire or metal tape, of sounds, and the primary object of the invention is to provide simplified apparatus and method for this purpose wherein the magnetic impulses are concentrated and confined to a smaller area of the wire or tape, so that the recording and reproduction is more free of noise and imperfections, and a shorter length of wire or tape is required for a given record thereon.

Other important objects and advantages of the invention will be apparent from a reading of the following description taken in connection with the appended drawings, wherein for purposes of illustration I have shown a preferred embodiment of my invention.

In the drawings—

Figure 1 is a general side elevational view of the embodiment.

Figure 2 is a longitudinal vertical sectional view taken through Figure 1.

Figure 3 is a top plan view of Figure 1.

Figure 4 is a horizontal sectional view taken along the line 4—4 of Figure 2 and looking in the direction of the arrows.

Figure 5 is a transverse vertical sectional view taken through Figure 1 at right angles to the view shown in Figure 2.

Figure 6 is a horizontal sectional view taken along the line 6—6 of Figure 5 and looking in the direction of the arrows.

Figure 7 is a side or edge elevational view of the core.

Figure 8 is a top plan view of Figure 7.

Figure 9 is an enlarged fragmentary transverse vertical sectional view with the concentrated magnetic flux illustrated in phantom lines with respect to the tape or wire and the core and surrounding elements.

Figure 10 is a perspective view of a wire with respect to which the recording and reproduction may be carried on.

In accordance with the present invention the magnetic impulses used to affect the steel wire or tape for the purposes of the invention, are concentrated in a comparatively small cross section pencil so that they will occupy as little space as possible so that the recording may be made at a slower wire or tape speed, with consequent reduction of unwanted noises in the reproduction.

The apparatus shown in the drawings com- 55 30 is that over which the steel wire or steel tape

prises the U-shaped core 5 which is in the present embodiment, rectangular in cross section and composed of the bight portion 6, the opposed vertical legs 7 and 8, respectively, and the pyramidal terminal portions 9 and 10, respectively, on the upper ends of the legs which lean toward each other as illustrated in Figures 2 and 9 with their points close together. The bight portion 6 has a suitable winding 11 thereon which extends between the uprights 7 and 8, this winding having one end thereof connected to the binding post 12 and the other end thereof connected to the binding post 13, a suitable source of alternating current being connectible to the said binding posts to set up the necessary alternating magnetic flux in the core 5.

Between the points 9 and 10 of the core and conforming to the space therebetween and above the winding 11 is the block 12 of metallic conductive but non-magnetic material which is insulated as indicated by the numerals 13 and 14 from the inner surfaces of the points 9 and 10 as clearly shown in Figure 9 of the drawings, with the apex 15 of the body 12 located slightly above the materials of the points 9 and 10. The block 12 merges into a heavy disk-shape 16 which has square openings 17 and 18 to accept the arms 7 and 8 of the core, with insulating material 19 and 20, respectively, completely insulating the core from the said openings. In addition, the disk form 16 is slotted at the diametrically opposed points 21 and 22, aligned with the legs of the core, these slots receiving insulation as indicated by the numerals 23 and 24, respectively. The gaps provided by the insulation material containing slots 21 and 22 are provided to prevent shorted turns of conducting material around the core. The periphery 25 of the disk form 16 is indicated by the numeral 27 and this insulating material extends in a frustro-conical form as indicated by the numeral 27 to cover the top of the disk-like form and the tops or radially outward sides of the points 9 and 10 of the core 5. The insulation 27 is interrupted over the point 15 of the body 12 as shown in Figure 9 to provide an aperture around the point 15. Above the block 12 and disk form 16 is the annular block 28 which is formed of conductive but non-magnetic material. The underside of the block 28 conformably fits the frustro-conical shaped insulation 27 and has a convex rounded top 29 and has a downwardly flaring opening 30 at its center which registers in concentrically spaced relation with the point 15. The opening

31 is drawn to receive the concentrated magnetic impulses produced by energization of the core 5. The top 29 of the block 28 has a groove 32 formed therein to guide the wire or tape 31 as indicated in Figure 3 or may be provided on this area with wear resisting material. Hinged at the point indicated by the numeral 33 at one side of the path 32 is the conductive non-magnetic material disk 34 which has a relatively small hole 35 at its center which is registered with the wire or tape 31 and with the opening 30. The disk 34 is formed and arranged to concentrate the magnetic impulses on the wire or tape 31. The casting 26 is arranged as a shield for the entire device and may be of either magnetic or non-magnetic material.

In the arrangement and operation of the device described, advantage is taken of the existence of eddy currents and their demagnetizing effect. When an alternating current is passed through the coil 11 a varying and alternating magnetic flux is set up in the core 5. At the points 9 and 10 the flux will not readily pass through the block 12 and disk form 16 because of the eddy currents produced in the block and disk form. Instead the varying part of the flux is directed toward the block 28 overlying the point of the core. Because of the action of the eddy currents, the body 28 tends to concentrate the pulsating parts of the flux into the small opening 30 in the center of this body, the disk 34 heightening and confining the concentration thus produced to a relatively small area or cross section of the record wire or tape 31 which overlies the opening 30 in any direction.

It is obvious that for reproducing from a record wire or tape, the arrangement described may be connected to the input of a suitable amplifier and the wire drawn past the opening 30, so that the passage of the wire or tape will induce currents in the winding of the core.

Although I have shown and described herein a preferred embodiment of my invention, it is to be definitely understood that I do not wish to limit the application of the invention, except as may be required by the scope of the subjoined claims.

Having described the invention, what is claimed as new is:

1. A recording and reproducing device of the character described, said device comprising a U-shaped core having a winding thereon, said core having laterally inwardly deflected tapered terminals on its legs terminating in relatively closely spaced small points, a non-magnetic conductive block surrounding and extending between said terminals and insulated therefrom, said block being formed with flux pencil forming opening above said points and of relatively small size.

2. A recording and reproducing device of the character described, said device comprising a U-

shaped core having a winding thereon, said core having laterally inwardly deflected tapered terminals on its legs terminating in relatively closely spaced small points, a non-magnetic conductive block surrounding and extending between said terminals and insulated therefrom, said block being formed with flux pencil forming opening above said points and of relatively small size, a second non-magnetic conductive material block overlying and insulated from the first mentioned block, said second block being formed with a second flux pencil forming opening registered with the first-mentioned flux pencil forming opening and across which the wire or tape to be impressed is drawn.

3. A recording and reproducing device of the character described, said device comprising a U-shaped core having a winding thereon, said core having laterally inwardly deflected tapered terminals on its legs terminating in relatively closely spaced small points, a non-magnetic conductive block surrounding and extending between said terminals and insulated therefrom, said block being formed with flux pencil forming opening above said points and of relatively small size, a second non-magnetic conductive material block overlying and insulated from the first mentioned block, said second block being formed with a second flux pencil forming opening registered with the first-mentioned flux pencil forming opening and across which the wire or tape to be impressed is drawn, and a flux confining and concentrating body of non-magnetic conductive material overlying the said second block and said wire or tape, said body being formed with an opening registrable with said second flux pencil forming opening.

4. A recording and reproducing device of the character described, said device comprising a U-shaped core having a winding thereon, said core having laterally inwardly deflected tapered terminals on its legs terminating in relatively closely spaced small points, a non-magnetic conductive block surrounding and extending between said terminals and insulated therefrom, said block being formed with flux pencil forming opening above said points and of relatively small size, a second non-magnetic conductive material block overlying and insulated from the first mentioned block, said second block being formed with a second flux pencil forming opening registered with the first-mentioned flux pencil forming opening and across which the wire or tape to be impressed is drawn, and a flux confining and concentrating body of non-magnetic conductive material overlying the said second block and said wire or tape, said body being formed with an opening registrable with said second flux pencil forming opening, and a shielding container enclosing said core, said winding, and the first and second blocks.

ALEXANDER B. CLOPTON.
